Frederick J. Stollsteimer, Miami Beach, Fla.

Application October 2, 1945, Serial No. 122,454

Term of patent 3½ years

(Cl. D31—2)

To all whom it may concern:

Be it known that I, Frederick J. Stollsteimer, a citizen of the United States of America, residing at Miami Beach, in the county of Dade and State of Florida, have invented a new, original, and ornamental Design for Bird Feeders, of which the following is a specification, reference being had to the accompanying drawing, forming part thereof.

Figure 1 is a top plan view of a bird feeder, showing my new design,

Figure 2 is a side elevation thereof,

Figure 3 is a front elevation thereof.

I claim:

The ornamental design for a bird feeder, as shown.

FREDERICK J. STOLLSTEIMER.
